(57) **CLAIM**

The ornamental design for a soccer training course, as shown and described.

DESCRIPTION

FIG. 1 is an isometric view of a soccer training course embodying my new design;

FIG. 2 is a front elevation view thereof; the rear elevation view being a mirror image thereof;

FIG. 3 is a right side elevation view thereof, the left side view being a mirror image thereof; and,

FIG. 4 is a top plan view thereof.

The broken lines showing the environment of the soccer training course are for illustrative purposes only; and form no part of the claimed design.
